UNITED STATES PATENT OFFICE.

AUGUSTO H. DE GOENAGA, OF GOBLEVILLE, MICHIGAN.

COMBINED POCKET-CASE AND STERILIZER FOR SURGICAL INSTRUMENTS.

1,223,675.

Specification of Letters Patent. Patented Apr. 24, 1917.

Application filed September 7, 1915. Serial No. 49,831.

To all whom it may concern:

Be it known that I, AUGUSTO H. DE GOENAGA, a citizen of the United States, residing at Gobleville, county of Van Buren, 5 State of Michigan, have invented certain new and useful Improvements in Combined Pocket-Cases and Sterilizers for Surgical Instruments, of which the following is a specification.

10 This invention relates to improvements in combined pocket cases and sterilizers for surgical instruments.

The main object of my invention is to provide a combined pocket case and sterilizer 15 for carrying thermometers, hypodermic syringes and other small surgical instruments, which is compact and of convenient form for carrying in the pocket, and also one which is easily charged with the sterilizing 20 material.

Further objects, and objects relating to structural details, will definitely appear from the detailed description to follow.

I accomplish the objects of my invention 25 by the devices and means described in the following specification. The invention is clearly defined and pointed out in the claims.

A structure which is a preferred embodiment of my invention is clearly illustrated 30 in the accompanying drawing, forming a part of this specification, in which:

Figure I is a side view of a structure embodying the features of my invention.

Fig. II is a top view of the structure shown 35 in Fig. I.

Fig. III is a vertical section on a line corresponding to line 3—3 of Fig. II.

Fig. IV is a vertical section on a line corresponding to line 4—4 of Figs. I and III.

40 In the drawing similar reference characters refer to similar parts throughout the several views, and the sectional views are taken looking in the direction of the little arrows at the ends of the section lines.

45 Referring to the drawing, my improved case and sterilizer comprises an outer casing 1, preferably flattened in cross section to fit a pocket. The casing is provided with a central threaded neck 2 for the casing closure cap 3. This cap is provided with a gasket 4 disposed within the cap to be clamped down on the end of the neck 2 forming a tight joint for the closure. At each side of the central neck 2 the casing

50 top is provided with openings 5 in which the tubular containers 6 are arranged and se-

cured with their ends projecting above the top of the casing and threaded to receive the container closure caps 7. These caps have sealing gaskets 8 which are clamped down 60 upon the ends of the containers. The containers have perforations 9 in their inner walls, so that the interior of the containers is in communication with the interior of the casing, allowing circulation through the 65 casing from the containers.

The containers illustrated are adapted to receive surgical instruments, such as hypodermic syringes, thermometers, and other instruments. The size and shape of the containers may be modified, if desired, to adapt 70 them to the particular instruments to be carried therein. The tubular form shown, however, is well adapted to receive different sizes and forms of instruments. 75

On the closure cap 4 is a rod 10 which depends into the casing between the containers and is removable from the casing with the cap. This rod carries a roll of absorbent material 11, which is removable with 80 the rod. This absorbent material may be wicking or other suitable material. In practice the rod with the absorbent material thereon is dipped into the sterilizing or disinfecting solution, such as formaldehyde, 85 and placed in the casing, the cap being screwed tightly to seal the casing. The fumes from the evaporation fill the casing and pass into the containers enveloping the instruments contained therein. The absorbent material may be charged frequently, as desired, but it is found that one charging 90 will last for several hours in the event that the casing and container caps are closed tightly and are opened only as it is necessary 95 to insert or remove the instruments.

My improved case and sterilizer is simple and economical to produce and is effective and very convenient.

I have illustrated my improvements embodied in a simple and practical form. The size and shape, however, may be, as stated, varied to accommodate the particular requirements. 100

Having thus described my invention, what I claim as new and desire to secure by Letters Patent, is:

1. A pocket case and sterilizer for surgical instruments, comprising a casing having a central threaded neck at the top and 110 openings through the top at the sides of the neck, tubular instrument containers ar-

1
1,223,675

ranged in said openings to project from the top, the projecting ends of said containers being threaded, the inner walls of said containers being perforated, caps for said containers, a closure cap for said casing threaded on said neck, a rod depending from said casing cap, and absorbent material carried by said rod, said absorbent material being adapted to be inserted and removed through 10 said casing opening.

2. A device of the class described, comprising a casing, a removable closure therefor, a rod depending from said casing closure, absorbent material carried by said rod, said material being removable from said casing with said closure, instrument containers arranged in said casing and open to the interior thereof to permit circulation from the casing therethrough, and closures 15

for said containers independent of said casing closure. 20

3. A device of the class described, comprising a casing, a removable closure therefor supported by a single wall of said casing, absorbent material removable from said casing with said closure, an instrument container arranged in said casing and open to the interior thereof to permit circulation from the casing therethrough, and a closure for said container independent of said casing closure. 25 30

In witness whereof, I have hereunto set my hand and seal in the presence of two witnesses.

AUGUSTO H. DE GOENAGA. [L. S.]
